Primary Examiner—Lucy Lieberman

[57] CLAIM

The ornamental design for a bottle, as shown and described.

DESCRIPTION

FIG. 1 is a top, front and left side perspective view of a bottle showing my new design.

FIG. 2 is a front elevation of the bottle of FIG. 1, the rear elevation is a mirror image thereto.

FIG. 3 is a left side view of the bottle of FIG. 1.

FIG. 4 is a right side view of the bottle of FIG. 1.

FIG. 5 is a top plan view of the bottle of FIG. 1; and,

FIG. 6 is a bottom view of the bottle of FIG. 1.

The broken lines showing a bottle neck are for illustrative purposes only and do not form part of the claimed design.
